Primary Examiner — Brett Miller*Assistant Examiner* — Jessica M Gebhart(74) *Attorney, Agent, or Firm* — Bridgeway IP Law Group, PLLC; Jihun Kim; Hyun Woo Shin(57) **CLAIM**

The ornamental design for a passport holder, as shown and described.

DESCRIPTION

FIG. 1 is a front, top, right side perspective view of a passport holder, showing our new design;

FIG. 2 is a rear, top, left side perspective view thereof;

FIG. 3 is a front elevation view thereof;

FIG. 4 is a rear elevation view thereof;

FIG. 5 is a left side elevation view thereof;

FIG. 6 is a right side elevation thereof; and

FIG. 7 is a top plan view thereof;

FIG. 8 is a bottom plan view thereof; and,

FIG. 9 is a front, top, right side perspective view thereof showing a configuration of use.

The broken lines in the drawings show portions of the passport holder that form no part of the claimed design.

1 Claim, 9 Drawing Sheets(56)
